UNITED STATES PATENT OFFICE.

PERCIVAL GEORGE GRAHAM, OF ENFIELD, NEAR SYDNEY, NEW SOUTH WALES,
AUSTRALIA.

LUBRICATING APPARATUS.

Application filed December 3, 1925, Serial No. 73,011, and in Australia November 2, 1925.

- This invention relates to lubricating apparatus but more especially refers to the lubrication of axles or the journals of wheels of any description and it has for its object 5 the provision of means for ensuring that the journal or axle be constantly supplied with lubricant under all conditions as long as there is any lubricant in the well, thus preventing hot boxes and torn brasses.
- 10 A further object is to provide an apparatus for this purpose which shall be simple and capable of easy installation and which shall have few parts and a long life.
- Accordingly there is provided a series of 15 rollers supported centrally below the journal or axle in such a manner as to press continually against it. The rollers which are mounted upon a spindle so that they may revolve with the journal consist of spaced 20 discs undercut so as to leave a thin rim and a thin web. They dip into the oil in the reservoir and as they revolve they throw the oil outwards and upwards onto the journal in a continuous stream.
- 25 In the drawings a lubricator constructed according to this invention and fitted to a railway box of a well known type is shown.
- Figure 1 is an end elevation showing the journal and the device and the means for 30 keeping it in position.
- Figure 2 is a side elevation of same, and Figure 3 is a plan of the device.
- The journal 4 is of well known type and is housed within a box 5 of the type which 35 has brasses of well known construction and a removable front plate 6.
- The lubricating device consists of a series of rollers 7 mounted on or formed integral with a spindle 8 which runs in bearings 9.
- 40 The rollers are kept against the underside of the journal 4 by the semi-elliptical spring 10 which bears against the bottom of the box 5 and is attached to each of the bearings 9. The spring also allows for any rocking 45 movement of the journal relative to the box.
- The spindle is kept in a central position laterally by the distance pieces 11 which bear against the parallel members 12 bolted to the bottom of the box, while longitudinal 50 movement is prevented by the member 13 which bears against one end of the device
- the other end being kept against the rear of the box 5.
- The rollers 7 are provided with a thin rim and a central web 15 and are normally half immersed in the lubricant. On the journal revolving the rollers are caused to rotate and the lubricant on the inner side of the rims and on the webs is thrown upwards and outwards onto the journal and in addition is transferred directly by the actual contact between the drums and the journal.
- The device may be easily fitted to any type of axle box provided that it has means or can be provided easily with means for 65 keeping it in position laterally and longitudinally. For example, boxes adapted for use with the well known pad system usually have integral parallel members such as 12 and by providing means such as 13 for preventing longitudinal displacement the device 70 may be easily fitted, being inserted through the plug in the front of the box.
- In order to prevent waste and leakage of the lubricant along the axle some sealing 75 means of any well known type is provided.
- I claim:—
- A device of the character described including in combination a journal, a box arranged thereabout, a pair of spaced parallel 80 longitudinally extending and vertically arranged guides on the floor of the box, a spindle, a series of rollers thereon, a pair of bearings for accommodating the ends of the spindle, opposed distance pieces projecting from each of the bearings and contacting with the inner surface of the guides, spaced arms depending from each of the bearings, a bowed spring having its medial portion engaging the floor of the bearing 90 with its respective ends pivotally connected between the arms of the bearings for normally holding the rollers in yielding engagement with the journal, and a device secured to the inner surface of the outer wall of the 95 box and engaging the outer end of the spindle for preventing longitudinal movement thereof, substantially as and for the purposes set forth.
- In testimony whereof I have signed my 100 name to this specification.

PERCIVAL GEORGE GRAHAM,
